ABSTRACT: A stabilizing tube, fixed to the hull of a boat below the waterline thereof with an inlet and an outlet respectively at the bow and the stern of the boat, has its midsection provided with water-expulsion holes which can be obstructed by a slider and open into the surrounding water to facilitate transverse steering. A rudder is mounted near the outlet end of the tube while a propeller in the tube at its inlet end serves to drive the boat forward or backward. The flow of water through the tube can be blocked by a valve just rearwardly of the expulsion holes.

SHEET 3 OF 3

MOTORBOAT

This invention relates to a motorboat having at least one stabilizer tube which is arranged under the waterline substantially in the longitudinal direction of the boat and substantially horizontal as well as substantially in a straight line in or on the boat's hull and firmly connected thereto, also including means adapted to drive water through the stabilizer tube, characterized in that the rudder blade is arranged directly behind the stabilizer tube in the stream expelled from the tube, the stabilizer tube being provided substantially in the longitudinal center of the lateral plane of the boat both on the port side as well as on the starboard side, with water-expelling openings selectively closable and throttling, means being provided for completely or partially closing one of the mouth ends of the stabilizer tube.

Propulsion of the boat is then effected on the one hand by the suction or pulling action at the water inlet mouth and on the other hand by the reacting force of the water column at the outlet mouth of the stabilizer tube. With only one stabilizer tube, the same will preferably be led through the body of the boat lengthwise in the middle thereof. On the other hand, with the adoption of several stabilizer tubes, these are preferably arranged symmetrical with the longitudinal axis of the boat. For dealing with special problems, it is possible to have arrangements of stabilizer tubes, with the tubes extending symmetrically from the bow towards the sides of the boat or symmetrically from the sides of the boat towards the stern. Alternatively it is possible to have several stabilizer tubes arranged one above the other to ensure optimum driving conditions for different amounts of loading of the boat (different draughts).

Moving the boat backwards is achieved by corresponding reversal of the movement of the water column. The steering of the boat is effected by a rudder blade arranged immediately behind the stabilizer tube, and additionally, with the adoption of several stabilizer tubes, by selectively throttling or opening the starboard or port lateral water-expelling openings.

The adoption of stabilizer tube drives, in conjunction with ship propellers, turbines or pumps, introduces a whole series of advantages, of which the following may be mentioned:

1. Because of the considerable weight of the water present in the stabilizer tube and uniformly distributed along the boat's hull, as well as because of the inertia of the linearly moved water column, the boat is strongly stabilized lengthwise, and receives also a corresponding stabilizing when several stabilizer tubes are arranged symmetrically.
2. A substantial portion of the water otherwise displaced by the bow is led through the body of the boat so as to considerably diminish the hydraulic drag.
3. Because of the uniform expulsion of water at the stern, the flow conditions become much quieter, with a corresponding diminution of the wake.
4. Because of the reactive force of the water column confined in a concentrated jet, a very much shorter braking distance is attained, particularly before obstacles in which the jet impinges (for instance quays).
5. Because of the rudder blade being located in the expelled stream from the stabilizer tube, particularly favorable maneuverability is ensured.
6. Because of the drive of the boat being located within the boat and/or tube, the possibility of injuries or damage being caused by floating bodies is practically excluded.
7. The application of symmetric lateral expelling openings and corresponding throttle valves on and/or in the stabilizer tube enables the boat to move easily transversely, so that it is possible to approach sideways easily to the quay and also to a drowning person without danger.

For this purpose the selectively closable or throttling water-expulsion openings in the stabilizer tube both at the port side and starboard side, as well as the device for shutting down the cross-sectional area of flow entirely or partly, serve to enable the water to flow out as desired to a great extent or entirely sideways instead of backwards. The arranging of the lateral water-expulsion openings in the region of the longitudinal

center of the lateral plane of the boat has thus the advantage that the water-expulsion openings do not emerge from the water, even when they are heavy waves, so that the action remains uniform. Another merit of this special arrangement of the water-expulsion openings in the region of the longitudinal center of the lateral plane is to be seen in the fact that the reactive force of the issuing jet of water exerts no torque tending to turn the board round its vertical axis, but drives the boat accurately transversely.

10 The accompanying drawing shows by way of example three forms of embodiment incorporating the invention therein:

FIG. 1 shows the plan of the boat according to the first form, with cross-sectional profile drawn hatched;

15 FIG. 2 is an elevation to FIG. 1, with details in vertical section;

FIG. 3 is a plan of the second form of the boat, with cross-sectional profile drawn hatched;

10 FIG. 4 shows an elevation to FIG. 3, with details in vertical section;

20 FIG. 5 is a plan of the third form of the boat, with cross-sectional profile drawn hatched, and

FIG. 6 is an elevation corresponding to FIG. 5, with several parts in vertical section.

25 Referring to FIGS. 1 and 2, reference character 1 designates the hull of a boat or of a motorboat. The bow of the boat houses the motor 2 inclined downwards to the front and serving to drive a shaft 4 through a gear 3, a screw 5 designed as propeller being arranged on the free end of the shaft. The

30 propeller projects into the interior of a tube 6 which extends lengthwise of the hull of the boat and passes therethrough under the waterline WL-WL. Approximately in the longitudinal middle of the boat or of the lateral plane thereof, the stabilizer tube 6 is provided at the port and at the starboard side

35 with additional water-expulsion openings 9 which can be selectively held open, throttled or even completely closed by means of valves 10, 10' arranged at both sides of the tube. Said valves are actuated by two hand levers 11, 11' which are pivoted to the hull at 12 and are connected with their forked

40 ends through linkage to the valves 10, 10'. Numeral 13 denotes a throttle valve fitted into the stabilizer tube 6; by means of the valve 13 the cross-sectional area of flow of tube 6 can be either throttled or completely closed. The throttle valve 13 is actuated by a handwheel 14 which is operatively connected thereto through a linkage 15. Finally, numeral 16 denotes the rudder blade which can be turned round a vertical axis in the longitudinal central plane of the stabilizer tube 6.

45 Power and movement of the engine 2 are transmitted in the usual manner through gear 3 and the shaft to propeller 5 which draws water in through the water inlet 7 at the stem of the boat and expels the water column present in tube 6 against the rudder blade 16 at the outlet 8 at the stern. Propulsion of the boat is effected under the suction action of propeller 5, and additionally by the reaction of the column of water issuing through the stern opening 8 of tube 6.

50 Should the boat have to be directed transversely during a maneuver, for instance to port, throttle valve 13 is closed more or less or even altogether, and valve 10 at the starboard side is more or less opened. Thus the water drawn in by propeller 6 through stem opening 7 of tube 6 is expelled through the starboard openings 9, whereby the boat will be moved transversely to port. Since the openings 9 for the lateral expulsion of water are in the longitudinal middle of the lateral plane or in the region of the center of gravity of the lateral plane, the boat will be moved practically transversely, i.e. perpendicular to its longitudinal axis.

55 In the second form as shown in FIGS. 3 and 4, numeral 1 again designates the hull of the boat. In contrast to the aforementioned example, in the form according to FIGS. 3 and 4 provision is made of two motors 2, 2' which are connected through two gears 3 and 3' with two driving shafts 4 and 4', transmitting their power to two propellers 5 and 5'. In accordance with this, two stabilizer tubes 6 and 6' are provided 70 in mirror image arrangement with reference to the boat's lon-

itudinal axis. In the region of the water inlet and water outlet openings 7,8, the stabilizer tubes 6,6' extend lengthwise of the boat. For the sake of simplicity, the items 9-15 have been omitted in FIGS. 3 and 4. In other respects the handling and action are the same as in the aforedescribed form.

In the further example according to FIGS. 5 and 6, three stabilizing tubes 6,6',6'' are arranged. Accordingly, three motors 2,2',2'' are provided, each of which drives a shaft 4,4',4'' as well as a propeller 5,5',5'' through a shaft 3,3',3''.

As in the form according to FIGS. 1 and 2, the lateral water-expelling openings 9,9' are provided only in the stabilizer tube 6 disposed in the longitudinal central plane of the board. In contrast to the example as in FIGS. 1 and 2, in the form according to FIGS. 5 and 6, instead of the two valves 10,10' for closing or opening the lateral water outlets 9,9', there is provided one drum 10'' which can be turned round its longitudinal central axis. Said drum is operable by means of a hand-crank 19 through a chain gear 18 arranged in a casing 17. Also in contrast to the example as in FIGS. 1 and 2, in the form according to FIGS. 5 and 6, instead of the throttle flap 13, there is arranged a slide valve 13' by means of which the cross-sectional area of flow of the stabilizer tube 6 can be throttled or shut down completely. Raising or lowering of valve 13' is brought about by a spindle 21 arranged in a casing 20 and connected to a handcrank 23 through a chain gear 22. Reference characters 16,16',16'' denote three rudder blades disposed in the vertical longitudinal central planes of stabilizer tubes 6, 6', 6''. Also in this case, the handling and action are the same as in the embodiment according to FIGS. 1 and 2.

In order to ensure a good stabilizing effect, the diameter of 30

the stabilizer tube (or tubes) should have a value not less than half the draught of the boat.

What I claim:

1. A stabilizing system for a boat having a hull, comprising a tube fixed to the hull longitudinally of the boat being the waterline thereof, said tube having an inlet and an outlet respectively at the bow and the stern of the boat and having a plurality of axially spaced lateral holes in its midsection opening directly into the surrounding water;
- 10 propulsion means adjacent said inlet; shutter means in said tube intermediate said holes and said outlet for selectively blocking the flow of water through said tube;
- 15 a rudder movably connected to the hull and extending outside said tube adjacent said outlet; slider means in said tube juxtaposed with said midsection for selectively opening and closing said holes, said slider means having axially spaced openings respectively alignable with said holes; and operating means for axially shifting said slider means between an obstructing and a nonobstructing position.
- 20 2. A system as defined in claim 1 wherein said shutter means comprises a rotatable valve disk and a lever linked therewith for rotating same.
- 25 3. A system as defined in claim 1 wherein said slider means comprises an elongated perforated plate, said operating means including a handle engaging said plate and projecting from said tube.
